UNITED STATES PATENT OFFICE.

WILLIAM J. BAILEY, OF CLEVELAND, OHIO.

DESIGN FOR A HELP-SELF COUNTER.

55,584.

Specification for Design.

Patented July 6, 1920.

Application filed April 17, 1920. Serial No. 374,764. Term of patent 14 years.

To all whom it may concern:

Be it known that I, WILLIAM J. BAILEY, a citizen of the United States, residing at Cleveland, in the county of Cuyahoga and State of Ohio, have invented a new and original Design for a Help-Self Counter, of which the following is a specification, reference being had to the accompanying drawings, forming a part thereof.

In said drawing, Figure 1 is an elevation and Fig. 2 is a section.

I claim;

The design for a help self counter substantially as herein shown.

WILLIAM J. BAILEY.
